UNITED STATES PATENT OFFICE.

EMANUEL AUFIERO, OF BROOKLYN, NEW YORK.

TIMEPIECE.

No. 927,472.

Specification of Letters Patent. Patented July 13, 1909.

Application filed June 22, 1908. Serial No. 439,799.

To all whom it may concern:

Be it known that I, EMANUEL AUFIERO, a citizen of the United States, residing at Brooklyn, in the county of Kings and State 5 of New York, have invented certain new and useful Improvements in Timepieces; and I do declare the following to be a full, clear, and exact description of the invention, such as will enable others skilled in the art to 10 which it appertains to make and use the same.

My invention relates to improvements in watches or other timepieces.

It has for its object to provide for indicating standard or local time in different longitudes and to effect that end in a simple, inexpensive, and ready manner.

With these and other objects in view, the invention consists of certain novel features 20 of construction, combination and arrangement of parts, as will be more fully described and particularly pointed out in the appended claim.

In the accompanying drawing illustrating 25 the preferred embodiment of my invention, is illustrated a face or front view of the invention.

In carrying out my invention, I provide a watch or timepiece 1, preferably as disclosed 30 and having the usual hour and minute indicating mechanism. The dial proper 2, has suitably arranged thereon certain indicia in circular outline embracing names of certain cities arranged in east and west longitudes 35 and interiorly of said arrangement of cities a corresponding arrangement of the minutes of the hour is designated as in the ordinary manner. The names of the cities arranged in west longitude and east longitude are indic- 40 ative by being produced in colors of red and black, the former indicating east longitude and the latter west longitude, as will be readily understood. Certain other indicia is also arranged upon said dial in connection 45 with certain of the cities mentioned, the purpose of which will appear later on. It will be noted that a. m. and p. m. are indicated by the same designation employed to designate the longitudes the color used for west longi- 50 tude representing a. m. and that for west longitude representing p. m. alternately.

A separate dial 3, having indicated thereon in circular outline the numerals 1 to 12 indicative of the hours of the day, and over-lying 55 said hour dial is a minute hand 4, said hour

dial and minute hand being actuated, as above intimated in the usual way. Said dial has preferably star pointed-like marginal outlines for radially reading its characters or numerals in connection with the names of 60 the cities or places upon the dial.

It will be noted that by way of illustration in the use of the timepiece, should it be set, say, 8.30 a. m., New York time, this adjustment, while showing 8.30 a. m. said time, 65 would show 8.30 - 5 minutes = 8.25 p. m. for Singapore; 7.30 a. m. for Chicago; 6.30 p. m. plus 20 minutes = 6.50 p. m. for Madras; 5.30 a. m. for San Francisco; 1.30 p. m. for London, and so on, from which, it is 70 thought, the operation of the invention will be readily appreciated.

From the foregoing description taken in connection with the accompanying drawings, the construction and operation of the invention 75 will be readily understood without requiring a more extended explanation.

Various changes in the form, proportion and the minor details of construction may be resorted to without departing from the principle or sacrificing any of the advantages of 80 the invention, as defined in the appended claim.

Having thus described my invention, what I claim as new is:—

A time piece comprising a stationary dial having spaced there around the names of certain principal cities in the eastern and western hemispheres, said names being printed in different colors to distinguish anti and post 90 meridian times, and also having mathematical indicia used in connection with said names for correcting the time shown by subtraction and addition, said dial having minute graduations arranged there around, an hour element comprising a multi-pointed rotating dial located within the stationary dial and having characters indicative of the hours of the day to co-act with said graduations, and a single hand traveling over said rotating 95 dial and pointing to the minute graduations on said stationary dial.

In testimony whereof I have hereunto set my hand in presence of two subscribing witnesses.

EMANUEL AUFIERO.
